THERMIONIC TUBE

Edwin C. Ewing, Chicago, Ill., assignor to Zenith
Radio Corporation, Chicago, Ill., a corporation
of Illinois

Application April 1, 1941, Serial No. 386,377

8 Claims. (Cl. 250—27.5)

The present invention relates to vacuum tubes and particularly to certain features of construction whereby tubes of this character are improved for amplification purposes, have an extremely low noise level, and are especially free from microphonic noises.

It is one purpose of the invention to provide a tube of this character wherein the filament is given adequate rigidity without applying hazardous tension thereto.

It is a further purpose of the invention to provide a tube of this character wherein the filament to grid to plate spacing and arrangement are such as to cut out electrostatic side field and increase electron concentration where the filament grid plate spacing is such as to give the best amplification.

It is also a purpose of the present invention to provide a novel construction whereby the tubulation for exhausting the tube is maintained open during the sealing or pinch operation.

The features and advantages of the invention will appear more fully as the description proceeds in connection with the accompanying drawing. The drawing and description are illustrative only however and should not be considered as limiting the invention except insofar as it is limited by the claims.

In the drawing:

Fig. 1 is a sectional view, several times enlarged, taken lengthwise through a tube embodying my invention;

Fig. 2 is a sectional view taken on the line 2—2 of Fig. 1;

Fig. 3 is a sectional view similar to Fig. 1 but taken along the line at right angles thereto, illustrating a different form of plate construction, the remaining elements of the tube being the same;

Fig. 4 is a sectional view taken on the line 4—4 of Fig. 3; and

Fig. 5 is a perspective view of the plate element shown in Fig. 3.

Referring now in detail to the drawing, the present invention is embodied in a vacuum tube which comprises a suitable envelope 10 having therein a plate 11, two grids 12 and 13 and a filament 14. In the form of device shown in Fig. 1 the plate 11 comprises a coating of colloidal graphite applied to the inner wall of the envelope.

The coating consists of an end portion 15 to which there is attached a lead 16 coming through the top end of the tube and extending over into contact with the graphite coating. The plate 11

has two wing portions 17 and 18 which extend down outside the grids 12 and 13 parallel to the filament 14. These two wing portions 17 and 18 are placed opposite the flattened wall portions of the grids 12 and 13 and the wings do not extend around the envelope where the end wall portions 19 and 20 of the grids are located. I arrange the plate wings in this position with respect to the grid or grids in order to prevent electrostatic side field at the point where the grids are close to the envelope and would necessarily have to be close to the plate. Also, the arrangement of the plate wings as shown increases electron concentration at the areas where the grids are closest to the filament. Low amplification characteristics are thus avoided and the electron concentration is at the most desirable point.

In Figs. 3 to 5 the plate 11' is somewhat differently constructed to the plate 11 but functions in the same manner. I use a metallic plate which may be wire mesh or solid. The wings 17' and 18' are positioned with respect to the grids 12 and 13 precisely as they are in Fig. 1. It is easier with the plate 11' to support it with a supporting wire 21 which passes out through the press of the tube and forms a lead-in wire for the plate. The plate 11' may also be used to carry a getter material 22 of any known type.

Referring now to the grid and filament mounting, the two grids 12 and 13 are composed of helical coils of wire mounted on suitable posts in a well known manner. A ceramic bead 23 made of a suitable ceramic material having adequate mechanical strength is used to connect certain of the elements of a tube such as the two grids 12 and 13. The bead is composed of a cold moldable, cold setting plastic material preferably of a ceramic base. The plastic bead 23 is of particular advantage in tubes of very small dimensions like that shown herein. Glass beads or others requiring heat cannot be used successfully. The heat would seriously injure the parts because of their size, particularly the filament. Also, the deleterious oxidizing of the parts that results from using heat in securing them together is avoided by use of the cold setting plastic ceramic material. As shown herein, the grids are connected together by a bead of this type and other elements are also joined by such beads. The long axis of the oval-shaped grids is placed parallel with the plane of the filament 14 and midway between the wing portions 17 and 18 or 17' and 18' of the plates. The grids are supported by separate lead-in wires 24 and 25 which are positioned by a glass bar 26. The

filament 14 has two leads 27 and 28. This filament is of course much smaller in diameter than the leads and is secured to them by a suitable mechanical connection.

I provide another bead 29 of ceramic material above the bar 26. The bead 29 serves to support a lateral guide hook 30 for the filament. Of course the guide hook 30 could be supported in some other fashion; for example, from the glass bead 26, or from the top of the assembly suitably insulated. The bead 29 is however a very simple and convenient means for supporting the guide hook.

The lateral guide hook comprises a stem portion 31, the base of which is mounted in the bead 29, and a rebent portion 32 at the free end of the stem 31. The base of the U-shaped filament 14 is passed between the stem 31 and the rebent portion 32 of the lateral guide hook. The hook is a loose fit so that the filament can slide up and down upon heating and cooling. I have found by experience that the filament coating does not loosen or wear at the point of contact with the hook and that the loss by heat conduction is negligible. I am aware that in the past it has been the practice to hook the midpoint of the filament up to suspension hook under more or less tension. Suitable tension on these delicate filaments is very difficult to apply. Moreover, tension in the filament aids vibration. By the use of the lateral guide hook as illustrated in the drawing I am able to give the filament rigidity in the right direction without applying hazardous tension thereto. The critical spacing of the filament is with respect to the adjacent wall portions of the grid that run parallel to the filament plane and are close to the filament. The guide hook keeps the filament from swinging so as to change this critical spacing. The filament, when the assembly is first completed, will bear against one side of the hook with a light pressure. However, when the filament is excited or heated the side pressure tends to decrease and the filament takes a permanent set so that there is merely a slight contact with the hook. Actual tests with many of the tubes having this construction show them to be quite free from microphonic noises. They have an extremely low noise level. Expansion or contraction of the filament does not place any strain thereon because of its freedom to slide lengthwise of the hook.

I have provided a novel means whereby to keep the tubulation for exhausting the tube open through the pinched end of the envelope. Prior to compressing the end of the envelope about the lead-in wires 24, 25, 27 and 28 I provide a thin tubular lining 33 within the tubulation glass. This lining 33 may be constructed of any suitable material. For example, it may be a metal tube or merely a coating of thick graphite placed inside the tubulator tube before the pinch operation. When the pinch operation is over the tubulator glass will be found to have a passage through which the tube may be exhausted. I find this of particular advantage in making the extremely small sized tubes to which the present invention is most applicable. As stated hereinbefore, the showing in Figs. 1 and 3 is multiplied several times in size over the actual tube. These tubes find considerable use in hearing aids. Their actual dimensions are usually about 1 inch overall length, including the pinched end portion, and the diameter of the envelope may be less than $\frac{1}{8}$ of an inch.

The specific details as to characteristics of the tubes are published in the magazine "Electronics" for February, 1941 (see page 67).

Having thus described my invention what I claim as new and desire to secure by Letters Patent is:

1. A vacuum tube comprising an envelope, a filament therein supported by its two ends, a grid encircling said filament and being flattened in cross section whereby two opposite wall portions thereof are in close proximity to the filament and the wall portions at 90 degrees from the first named wall portions are relatively remote from the filament, and a plate comprising an end portion and two wing portions extending lengthwise of the filament outside said first named grid wall portions but not outside said second named grid wall portions.

2. A vacuum tube comprising an envelope, a plate, a grid and an emitter in said envelope, said emitter including a loop filament supported therein by its two ends, and a lateral guide member loosely overlying said filament in proximity to the midpoint thereof, said filament being free to slide endwise in said member but being held against lateral swinging movement by said member.

3. A vacuum tube comprising an envelope, a plate, a grid and a U-shaped filament in said envelope, leads supporting said plate, grid and the ends of the filament in the envelope, and a lateral guide for said filament engaging it at approximately the midpoint, said guide having a channel in which the filament is slideable endwise, the channel damping vibration of the filament in a direction perpendicular to the plane of the filament.

4. A vacuum tube comprising an envelope, a plate, a grid and a U-shaped filament in said envelope, leads supporting said plate, grid and the ends of the filament in the envelope, a bead interposed between the filament and the envelope and mechanically connecting the filament leads to each other, and a lateral guide hook for the filament carried by said bead.

5. A vacuum tube comprising an envelope, a plate, a grid and a U-shaped filament in said envelope, leads supporting said plate, grid and the ends of the filament in the envelope, a glass bar between the envelope and the grid and filament mechanically connecting the leads, a bead interposed between the filament and the bar and mechanically connecting the filament leads to each other, and a lateral guide for said filament engaging it at approximately the midpoint, said guide having a channel in which the filament is slideable endwise, the channel damping vibration of the filament in a direction perpendicular to the plane of the filament, and said guide being supported by said bead.

6. A vacuum tube comprising an envelope, a plate, a grid and a U-shaped filament in said envelope, leads connected to the opposite ends of said filament and supporting it within said envelope, said grid encircling the filament and being flattened in cross section whereby two opposite walls thereof extend substantially parallel to the plane of the filament and in close proximity thereto, the portions of the grid connecting said opposite walls being relatively remote from the filament, a supporting lead connected to one of said connecting portions of the grid, said plate comprising two wing portions extending lengthwise of the filament outside of the aforesaid opposite walls of the grid and spaced apart at their

side edges whereby to leave the connecting portions of the grid with no plate portions outside of them, said wing portions being connected to each other by means extending over the ends of the grid and filament opposite said supporting leads and remote from said ends, whereby the electron concentration is greatest at the areas where the grid is closest to the filament and electrostatic side field is prevented at said connecting portions of the grid.

7. A vacuum tube comprising an envelope, a plate, a grid and a U-shaped filament in said envelope, said grid encircling the filament and being flattened in cross section whereby two opposite walls thereof extend substantially parallel to the plane of the filament and in close proximity thereto, the portions of the grid connecting said opposite walls being relatively remote from the filament, said plate comprising two wing portions extending lengthwise of the filament outside of the aforesaid opposite walls of the grid and spaced apart at their side edges whereby to leave the connecting portions of the grid with no plate portions outside of them, said wing portions being connected to each other by means extending over the ends of the grid and filament and remote from said ends, whereby the electron con-

centration is greatest at the areas where the grid is closest to the filament and electrostatic side field is prevented at said connecting portions of the grid.

- 5 8. A vacuum tube comprising an envelope, a plate, a grid and a U-shaped filament in said envelope, said grid encircling the filament and being flattened in cross section whereby two opposite walls thereof extend substantially parallel to the plane of the filament and in close proximity thereto, the portions of the grid connecting said opposite walls being relatively remote from the filament, said plate comprising two wing portions extending lengthwise of the filament outside of the aforesaid opposite walls of the grid and spaced apart at their side edges whereby to leave the connecting portions of the grid with no plate portions outside of them, said wing portions being connected to each other by a getter carrying disc extending over the ends of the grid and filament and remote from said ends, whereby the electron concentration is greatest at the areas where the grid is closest to the filament and electrostatic side field is prevented at said connecting portions of the grid.
